UNITED STATES PATENT OFFICE.

LUTIE MABEL KENNEDY, OF FULTON, ILLINOIS.

DESIGN FOR A TIRE-TREAD.

57,350.

Specification for Design. Patented Mar. 15, 1921.

Application filed April 10, 1920. Serial No. 373,014. Term of patent 7 years.

To all whom it may concern:

Be it known that LUTIE MABEL KENNEDY, a citizen of the United States, residing at Fulton, in the county of Whiteside, State of Illinois, has invented a certain new, original, and ornamental Design for a Tire-Tread, of which the following is a specification, reference being had to the accompanying drawing, forming a part thereof.

Figure 1 is a perspective view of a fragment of the tire showing the design thereon, and

Fig. 2 is a view of the design of the tire as it would appear looked at from the surface of the tread.

I claim:

The ornamental design for a tire tread, as shown.

In testimony whereof I hereunto affix my signature in the presence of two witnesses.

LUTIE MABEL KENNEDY.
